ATTORNEYS:

UNITED STATES PATENT OFFICE.

WILLIAM H. SAART, OF ATTLEBORO, MASSACHUSETTS, ASSIGNOR TO THE
JAMES E. BLAKE COMPANY, OF SAME PLACE.

DESIGN FOR A DISH OR SIMILAR ARTICLE.

SPECIFICATION forming part of Design No. 34,654, dated June 11, 1901.

Application filed May 21, 1901. Serial No. 61,308. Term of patent 3½ years.

To all whom it may concern:

Be it known that I, WILLIAM H. SAART, a citizen of the United States, residing at Attleboro, in the county of Bristol and State of Massachusetts, have invented and produced a new and original Design for a Dish or Similar Article, of which the following is a specification, reference being had to the accompanying drawings, forming part thereof.

Figure 1 is a plan view of a dish, showing my new design. Fig. 2 is a transverse section of the dish on the line X X of Fig. 1.

As shown in the drawings, the leading or material feature of my design consists of the convex central panel of ovoid outline contracted centrally and having on it the raised representation of a nude female figure surmounting the crest of a wave. The panel is inclosed in foliated scrolls and surrounded

by a border of bold convex cross-section or 20
ornamented by four raised figures representing winged dragons, which support panels having the raised representation of cupid-heads on a convex surface. The ends of the dish have shell ornaments overlaid by the foliated 25
tails of the dragons.

Having thus described my invention, what I claim as new, and desire to secure by Letters Patent, is—

The design for a dish or similar article, as 30
herein shown and described.

In testimony whereof I have signed my name to this specification in the presence of two subscribing witnesses.

WILLIAM H. SAART.

Witnesses:

A. E. HAGERTY,
JOSEPH A. MILLER.
